FLUID IMPELLER AND TURBINE

Chester W. Brown and Erwin F. Dosie,
Milwaukee, Wis.

Application May 23, 1932, Serial No. 612,928

19 Claims. (Cl. 103—115)

This invention relates to improvements in fluid impellers and turbines. While the device herein disclosed is described primarily as a fluid impeller for the purposes of the present invention, its moving part nevertheless has utility also as the runner or rotor of a fluid turbine or motor.

It is the primary object of the invention to provide a novel and improved rotor for devices of the indicated class, the said rotor being of such characteristics as to provide a maximum fluid capacity in comparison with its physical dimensions, and being adapted to handle large volumes of fluid with a minimum of eddy currents or other disturbances such as ordinarily tend to impede free flow of fluid through devices for imparting or receiving motion to or from the fluid passing therethrough.

More specifically stated, it is the object of this invention to provide a runner or rotor having an axially disposed inlet almost equal in diameter to the entire rotor and an outlet at least as great in area as the inlet, the said rotor being so designed as to provide a multiplicity of passages between the inlet and outlet, each adapted to receive fluid from a particular sub-divided portion of the fluid stream entering the inlet.

One of the desirable objectives of the construction herein disclosed is the provision of a device which, when operated as a fluid impeller, will draw fluid from an area almost equal to the area which it occupies, the suction or partial vacuum created in the operation of the device being approximately equal throughout said area. By reason of this feature the device is peculiarly adapted for use as a propeller, and some forms of the invention are calculated to deliver the fluid in a direction partially or entirely axial, whereby to be efficient in transforming rotative to axial motion.

It is a further object of the invention to provide a device in which the axial and radial forces developed in the operation of the device may be substantially neutralized whereby to eliminate thrust on the driving shaft.

A device made in accordance with this invention is useful for some purposes when operating unenclosed, and for other purposes it should be encased. For the latter purposes, it is one of the objects to provide an organization in which fluid admitted to a casing, housing a runner and made in accordance with this invention, will follow more or less smoothly a predetermined helical spiral path from the inlet to the discharge port of the casing without any abrupt change in direction, and without encountering any surfaces or ob-

structions such as might tend to create substantial eddy currents or other resistance factors.

In the drawings:

Figure 1 is a view partially in side elevation and partially in axial section, showing a rotor or runner device embodying the present invention. 5

Figure 2 is a front elevation of the device shown in Figure 1.

Figure 3 is a view partially in side elevation and partially in axial section, showing a modified embodiment of a rotor or runner device 10 incorporating the invention.

Figure 4 is a view similar to Figure 3 showing a further modification.

Figure 5 is an enlarged fragmentary view in perspective, of a single plate employed in the device shown in Figures 1 and 2, showing the arrangement whereby a spacer is embossed from said plate. 15

Figure 6 is a detail view on a reduced scale 20 showing the application of a specialized form of flat impeller embodying the invention to a motor armature shaft for use as a fan, the device being organized to balance or neutralize all forces to which the armature shaft is subject. 25

Figure 7 is a detail view in axial section through a fluid impelling device embodying the invention and including a runner somewhat similar to that shown in Figures 1 and 2.

Figure 8 is a front elevation of the device shown 30 in Figure 7, a portion of casing being broken away to expose the face of the runner or rotor.

Figure 9 is a front elevation of a modified form of rotor employing spokes to support each annulus directly from the shaft. 35

Figure 10 is a view in axial cross section through the device shown in Figure 9.

Figure 11 is a view in axial section illustrating an application of the device for propulsion.

Like parts are identified by the same reference 40 characters throughout the several views.

The rotor or runner shown in Figs. 1 and 2 includes a mounting plate 10 carried by a shaft 11. This plate preferably comprises a solid or imperforate disk to which are secured by bolts 45 12 a number of annular plates 15 which have internal openings of progressively increasing diameter, the said annular plates being spaced from each other as shown, to provide narrow circumferential slot-like passages for the discharge of 50 fluid. The means whereby the plates are spaced from each other may conveniently comprise integrally embossed portions 16 of the plates, as shown in Figs. 2 and 5, the spacing bosses being 55 preferably stream lined in the direction of fluid

delivery so as to involve minimum interference with the smoothness of fluid discharge. The embossed spacing portions 16 of the plates are apertured to receive the mounting bolts 12.

5 The resulting runner or rotor has an inlet opening almost as large in diameter as the full diameter of the rotor, the last plate 15 in the series preferably having very little radial extent, as shown in Fig. 2. The successively decreasing 10 radii of the openings of successive plates in the series leading toward the mounting plate 10 give the inlet the appearance of a conical inlet.

When the device is rotated, the centrifugal 15 force developed in the fluid contained in the channels between the plates 15 and plate 10 will cause all such fluid to flow toward the periphery of the several plates where it will be discharged uniformly in all directions. The fluid thus discharged will be replaced by other fluid moving 20 into the conical inlet, sub-divided by the several plates, and similarly discharged from the periphery.

The capacity of each of the radial discharge 25 passages between consecutive plates of the series will preferably be so chosen with reference to the differential area between consecutive plates at either side of the passage that the several 30 passages will handle substantially alike the annular column of fluid which encounters the exposed annular surface of the plate bounding the passage at its inner side. In other words, the flow will be uniform or substantially uniform across the entire diameter of the inlet, the incoming fluid being in effect sub-divided by the 35 inner margins of the several annuli into concentric tubular columns of fluid, each of which in turn will encounter a particular annulus adjacent its inner margins, and will flow radially across the face of such annulus to the constricted 40 annular space or discharge passage to the point of delivery. No vanes need be used in a device of this kind, the friction of the fluid on the surfaces of the plates being relied upon to ensure its centrifugal discharge.

45 While planiform plates have been shown in Figs. 1 and 2, it will be obvious to those skilled in the art that they may be made conical, as shown at 150 in Fig. 3. In the Fig. 3 construction the direction of discharge is somewhat toward the rear of the impeller.

50 In the Fig. 4 construction the plates 151 are similar to those shown in Fig. 3, but alternate plates are provided with peripheral extensions at 152 which curve rearwardly to discharge the fluid in an axial direction. The Fig. 4 construction discloses the fact that it is not necessary for all the plates to have an equal diameter, this being particularly true where the plates are converging and the radial passages between the 55 plates might be unduly restricted if all the plates had a like radial extent.

In Fig. 6 is shown a construction in which the annular plates 15 above the mounting plate 10 are duplicated by a lesser number of plates 65 15 below the mounting plate 10. The shaft 11 in this instance is disposed vertically and comprises the armature shaft of a motor 18. Such a device is highly useful as a table fan, and may also be used for many other purposes. The 70 greater number of plates above the mounting plate creates a greater vacuum above the rotor than that which exists beneath it, the differential being so worked out as to provide a force which, in the normal operation of the mechanism, will substantially equal the weight of the 75

armature shaft 11 and the fan. Since the forces resulting from a discharge of the fluid are balanced in all directions, and since the weight of the moving parts is also balanced in the full speed operation of the mechanism, the result will be that shaft 11 will substantially float in its bearings without any appreciable load thereon. 5

The construction shown in Figs. 7 and 8 is particularly designed for use as a pump. At relatively heavy mounting plate 110 is employed on the drive shaft 111 which turns in suitable bearings provided in casing 19. The removable closure 20 at the rear of the casing is recessed to receive the impeller mounting plate 110, and a similar recess in casing 19 receives the outer 15 annulus 21 of the series carried by the plate 110. The intermediate annuli 15 are identical with those disclosed in Figs. 1 and 2.

The spacing between the annuli, however, has been graduated to exemplify another aspect of 20 the invention, the plates having the largest openings being spaced farther apart than the plates at the other ends of the series where the central openings are small. This feature is of assistance 25 in maintaining a substantially uniform rate of fluid flow throughout all portions of the apparatus. The annuli first encountered by the inwardly moving fluid might, in some installations, tend to divert an undue proportion of the fluid were it not for means creating a greater 30 suction at the center. Within limits, the closer the plates are fixed with reference to each other, the greater will be their frictional action on the fluid, and hence the greater will be the suction produced. There will be a natural tendency for 35 the flow to be uniform throughout all parts of all of the devices disclosed herein, and the present embodiment showing a difference in spacing between plates is illustrative of means which may be employed to correct any difference in flow 40 which may be observed in a particular installation.

The casing 19 provides two annular chambers 22 and 25. The former is in registry with the inlet of the rotor or impeller and has a tangential fluid admission port 23. The discharge chamber 25 is concentric with and disposed about the periphery of the runner or impeller, and has a tangential outlet at 24 extending in the same direction in which fluid is traveling 50 when admitted to the casing through port 23. 45

The arrangement disclosed is such that fluid is at no time subjected to any sudden change of direction in traversing the device. It is given a helical movement in chamber 22 by the annular form of the chamber and by the disposition of the tangential admission port 23. It continues this helical movement in a spiral direction through the impeller and continues to rotate in chamber 25 toward the point of tangential discharge at 24. 55

The construction of the rotor shown in Figs. 9 and 10 is essentially similar to those previously disclosed herein with the single exception that the annuli 155, instead of being carried by a 60 mounting plate, are provided with spokes 156 and hub portions 157, and stamped integrally therewith, the latter being preferably provided with integral key tongues 158 for mounting directly upon the splined shaft 112. The thinness of the spokes minimizes their interference 65 with fluid entering the rotor through the graduated central apertures of its successive annuli. 70

Figure 11 illustrates a preferred application of the invention for propulsion of any device 75

through a fluid. The fact that the opening in the impeller is almost as large as the diameter of the propeller makes the device peculiarly useful as a propeller because it acts on almost all of the fluid which it displaces in its movement. The propulsion installation shown in Fig. 11 is adaptable for use in airships, submarines, torpedoes, outboard motors, and other bodies designed for movement through air, water or other fluids.

The body 30 to be propelled is preferably stream lined to present a torpedo contour with a fairly blunt nose as shown. An axially extending power shaft 31 drives an impeller unit 32 which may be exactly like those shown in Figs. 1 and 2, or like those shown in Fig. 3 or 10. The discharge from the impeller 32 is received into an annular space 33 between the outer surface 34 of body 30, and a correspondingly formed conical shell 35 spaced from the body by webs 36.

The suction produced at the inlet of impeller 32 upon rotation of shaft 31 has a very powerful propulsive effect on body 30, tending to move the body axially to the right as viewed in Fig. 11. A very substantial additional propulsive effect is created by the discharge of the fluid against shell 35 which turns the fluid rearwardly and receives a reactive force tending to propel body 30 toward the right as viewed in Fig. 11.

The fluid leaving shell 35 and passing outwardly across surface 34 of body 30 tends to follow a rectilinear path from which surface 34 deviates. Thus a partial vacuum is produced on surface 34 similar to that which is produced on the upper surface of an aerofoil in the flight of an airplane. This vacuum also is the cause of a tendency of body 30 to be propelled to the right as viewed in Fig. 11. Thus, in the Fig. 11 construction, the impeller, its casing and the form of the body with which the impeller and casing are used, are all co-operative to produce a propulsive effect on such body.

Devices of the character disclosed have been demonstrated to be remarkable in their efficiency because of the efficiency of the impeller, which, whether cased or operating in free space, is adapted to handle without loss of power an extremely large volume of fluid in proportion to its overall dimensions.

The various embodiments of the invention selected for illustration herein, are intended merely to exemplify a few of the many possible variations to which the invention is adapted. In each of the many fields in which the device is used there will necessarily be some adaptation of its form. Among the uses to which the device may be adapted it may be mentioned that it is suitable for use as a fan in propulsion of gaseous or liquid fluids; for use as a propeller operating either in gaseous or liquid fluids for the propulsion of air, land or water vehicles; for use as a pump for fluids of all kinds; for use in creating partial vacuums; for use in picking up and distributing light solids such as dust and flour, and for use in the circulation of fluids where no definite path of circulation is indicated, as for example, in circulating the air in a room without substantial draft.

The device herein disclosed is not only simple in construction and inexpensive to manufacture, but it is of unusual efficiency and may be standardized for any given power requirement.

One of the great advantages of the form of impeller herein disclosed lies in the fact that it may

be designed in advance to consume any given quantity of power at any given speed of operation. Unlike an ordinary propeller or pump, it does not require operation at relatively low speeds to maintain its efficiency. It will operate 5 efficiently even at the highest speeds at which a steam turbine or electric motor may be driven. Thus, the use of reduction gearing is made unnecessary and the full power of high speed turbines or driving motors may be consumed efficiently in a direct drive installation.

We claim:

1. An impeller comprising the combination with rotatable mounting means, of means providing fluid passages opening axially in opposite 15 directions and discharging peripherally, said passages having a differential capacity such that the reaction toward fluid admitted thereto will oppose the action of gravity on the impeller when the axis of rotation thereof is vertical.

2. In a device of the character described, a balanced rotor comprising a vertical shaft, a series of mutually spaced annuli having openings of large diameter at each end of the series, and openings of progressively decreasing diameter in 25 successive annuli toward a point intermediate the ends of the series, and means for supporting the several annuli from the shaft, the fluid handling capacity of the annuli below the point of minimum cross section of opening being less than the 30 capacity of the annuli above said point by an amount in such proportion to the desired speed of operation of the annuli that the differential reaction of fluid moving toward said point from the top and the bottom of the series of plates is 35 approximately equal and opposite to the force exerted by gravity on said shaft.

3. In a device of the character described, the combination with a vertical shaft and a mounting means carried thereby, of a series of annular 40 plates mutually spaced and having openings progressively increasing in diameter from a point intermediate the ends of said series of plates toward both ends thereof, said point being nearer the lower end of the series than the top end 45 thereof, whereby to establish a differential suction at the ends of the series tending to balance the weight of said shaft and plates.

4. In a device of the character described, the combination with a vertical shaft, of a rotor arranged for discharge substantially throughout its periphery, said rotor comprising a series of annuli, and means supporting said annuli from said shaft, said annuli having central openings progressively increasing in diameter toward the 55 ends of said series from a point intermediate such ends, the fluid impelling capacity of the annuli above said point being in excess of the fluid impelling capacity of the annuli below said point, whereby to tend to balance the weight of 60 said annuli and shaft, and radial forces to which said rotor is subjected by the reaction of the fluid impelled being substantially balanced.

5. In a device of the character described, a casing having substantially co-axial and substantially circular chambers provided respectively with tangential inlet and outlet passages opening directly thereto, the outer wall of each such passage being substantially flush with the periphery of the chamber with which it communicates, said casing providing an annular space affording communication between the outer periphery of the inner chamber and the inner periphery of the outer chamber, and a rotor arranged to revolve in said space and provided with 70 75

- openings leading from one of said chambers to the other, said rotor being turnable in the direction in which fluid rotates in both of said chambers in accordance with the direction of its tangential delivery into the first of said chambers and discharge from the second.
6. A device of the character described, comprising the combination with a casing providing an annular inlet chamber, a co-axial discharge chamber of larger diameter, said chamber being substantially circular, an annular space affording communication between said chambers, of inlet and outlet ducts disposed tangentially with respect to the respective chambers, whereby to induce circumferential flow of a fluid in the same direction throughout both said chambers, and a rotor comprising spaced annuli mounted in the annular passage between said chambers and provided with central openings communicating with the inlet chamber and radial discharge passages communicating with the discharge chamber, said rotor being arranged to rotate in the said direction of circumferential fluid travel in said chambers.
7. In a device of the character described, a casing provided with axially offset annular inlet and outlet chambers having substantially circular outer peripheries concentrically arranged and of different diameters, tangential inlet and outlet ducts leading to and from the respective chambers and so disposed as to accommodate fluid rotating continuously in the same direction, an annular passage leading directly from the largest diameter of the smaller chamber to the smallest diameter of the larger chamber, and a rotor positioned between said chambers in said passage and affording communication therebetween, said rotor comprising annuli of progressively decreasing opening across the end of the smaller chamber, and means connecting said annuli in mutually spaced relation, the annulus with the largest opening being presented to the inlet chamber and the spaces between said annuli being arranged to discharge directly into the outlet chamber.
8. In a device of the character described, the combination with a casing having concentric annular chambers of different diameters having substantially circular outer peripheral walls and being in axially offset relation, a shaft extending axially to said casing, and a rotor mounted on said shaft and affording communication between said chambers, said rotor comprising a series of mutually spaced annuli, the internal diameter of the annulus next to the smaller chamber being substantially equal to the maximum diameter of said chamber and directly communicating therewith and the spaces between said annuli being arranged to discharge into the larger chamber, the openings in the respective annuli being progressively decreased in diameter in accordance with their remoteness from the smaller chamber, the respective chambers having inlet and outlet ducts disposed tangentially to receive and discharge a fluid revolving in said chambers in the direction of rotation of said annuli.
9. The combination with a body requiring propulsion and having a generally conical bow, of a propelling rotor mounted to turn thereon in advance of said body and comprising spaced annular plates arranged to receive fluid from the path of advance of said body to discharge such fluid peripherally.
10. The combination with a body requiring propulsion and having a generally conical bow, of a propelling rotor mounted to turn thereon in advance of said body and comprising spaced annular plates arranged to receive fluid from the path of advance of said body to discharge such fluid peripherally, together with a deflecting apron arranged about said rotor in spaced relation to said body and positioned to deflect rearwardly the fluid discharged peripherally from said rotor.
11. The combination with a body requiring propulsion, of a propelling rotor mounted to turn thereon in advance of said body and comprising spaced annular plates arranged to receive fluid from the path of advance of said body to discharge such fluid peripherally, together with a deflecting apron arranged about said rotor in spaced relation to said body and positioned to deflect rearwardly the fluid discharged peripherally from said rotor, said body having a stream line form deviating from the path of discharge of fluid, whereby to receive propulsive movement occasioned by the void created by the discharge of such fluid.
12. In a device of the character described, the combination with a runner having fluid engaging portions, of a casing providing: a passage within which said portions are disposed, a first chamber of circular cross-section and elongated form opening at one end to said passage and provided adjacent the other end with a tangential port opening directly to said chamber with its outer wall substantially flush with the periphery of said chamber, and a second chamber of substantially annular form with the inner periphery of which substantially all portions of said passage communicate and which is provided with a tangential port disposed in a direction complementary to that of the first port, whereby fluid entering through one of said ports will rotate continuously in one direction in traversing said casing.
13. In a device of the character described, the combination with a chamber of circular cross-section and elongated form having a tangential port adjacent one end and being open at the other end, of a rotor disposed at the open end of said chamber and comprising a series of friction plates spaced in sufficiently close proximity to propel a fluid independently of vanes, the plate immediately adjacent said chamber having an aperture substantially identical in diameter with the diameter of said chamber and successive plates having apertures of successively reduced diameter, and means supporting said plates for rotation in the direction of rotation accommodated by said tangential port.
14. In a device of the character described, the combination with a chamber of circular cross-section and elongated form having a tangential port adjacent one end and being open at the other end, of a rotor disposed at the open end of said chamber and comprising a series of friction plates spaced in sufficiently close proximity to propel a fluid independently of vanes, the plate immediately adjacent said chamber having an aperture substantially identical in diameter with the diameter of said chamber and successive plates having apertures of successively reduced diameter, and means supporting said plates for rotation in the direction of rotation accommodated by said tangential port, the spacing between said plates being progressively decreased in a direction away from the end of said chamber.
15. In a device of the character described, the combination with a rotatable support, of a runner mounted thereon and comprising a series of

mutually spaced annular plates in sufficiently close proximity to propel a fluid independently of vanes, the spacing between said plates being progressively decreased and said plates having apertures progressively decreasing in diameter throughout the series and communicating with successive diminishing spaces between the plates, the fluid handling capacity of the spaces between the plates and the successive apertures being so chosen that the inter-plate space just beyond each aperture has a flow capacity substantially equal to the difference in capacity between that aperture and the next aperture of the series, whereby the fluid handled is acted upon substantially without eddy currents.

16. In a device of the character described, a rotor for fluid actuation comprising the combination of a series of plates spaced in sufficiently close proximity to each other to offer to fluid a high frictional contact per unit volume of fluid passing between the plates, upon which the propulsive reaction between the plates and such fluid is dependent substantially independently of vanes, said plates having substantially aligned openings for the admission of fluid to the successive inter-plate spaces, which openings progressively decrease in area in the entrance direction of air from an end of the series at which air is admitted, whereby said plates perform the dual function of propulsion and fluid proportioning.

17. In a device of the character described, the combination with a shaft, of a rotor arranged to discharge substantially unimpeded throughout its periphery, said rotor having annular plates in close proximity to each other with axially aligned central openings progressively decreasing in diameter from the end at which air is admitted to the series of plates toward the other, said openings communicating with the spaces between plates, and the plates being sufficiently close to comprise substantially the sole propelling medium of fluid engaged thereby, and means supporting the plates from the shaft and including spacers disposed with their greatest length in line with the path of fluid flow whereby to pass fluid with-

out substantial reaction thereon and without the creation of eddy currents, whereby said spaced plates perform the dual function of a propulsion means and a fluid proportioning means without any substantial loss of energy in induced eddy currents.

18. The combination with a body having a convex bow portion laterally streamlined toward its forward end, a drive shaft projecting forwardly from said end, a propelling rotor mounted on said shaft in advance of the body and comprising spaced annular plates substantially co-extensive with said end and arranged to receive fluid from the path of advance of said body and to discharge such fluid peripherally, and an apron having its forward portion apertured to fit substantially about one of the foremost of said plates and extending thence in streamlined contour in spaced relation to the streamlined sides of said body, whereby to deflect the peripheral discharge from said plates smoothly along the side of said body.

19. The combination with a body requiring propulsion and having a bow portion convexly formed to provide streamline surfaces terminating at a blunt nose, of a propelling rotor mounted in close proximity to said nose with its periphery arranged to discharge at said convex surfaces, said rotor comprising axially spaced annular plates having respective central openings progressively decreasing in size from the foremost of said plates toward the rearmost thereof, and an apron having means connecting it in spaced relation to said body to receive the peripheral discharge from said rotor and to guide such discharge rearwardly about the convex surfaces thereof, the forward margin of said apron being in close proximity to the foremost plate, and the rear margin of said apron being disposed somewhat rearwardly of the rearmost plate, the exterior of said apron being likewise of streamline form.
